UNITED STATES PATENT OFFICE.

MOSE BRUYERE, OF GREEN BAY, WISCONSIN.

CRUTCH AND CUSHION-TIP THEREFOR.

1,319,564.

Specification of Letters Patent. Patented Oct. 21, 1919.

Application filed June 17, 1919. Serial No. 304,801.

To all whom it may concern:

Be it known that I, MOSE BRUYERE, a citizen of the United States, residing at Green Bay, in the county of Brown, State of Wisconsin, have invented a new and useful Crutch and Cushion-Tip Therefor; and I do hereby declare the following to be a full, clear, and exact description of the invention, such as will enable others skilled in the art to which it appertains to make and use the same.

This invention relates to crutches, and particularly to an improved cushion tip for the lower end of the crutch, and one of the objects of the invention is to provide a simple, efficient and practical device of this kind, which may be manufactured at a small cost and sold at a reasonable profit.

A further object of the invention is the provision of a sleeve and slotted guides for a thimble tip, which is spring tensioned, the slotted guide acting to reinforce and prevent the thimble tip from rotating, while the sleeve guide (which is spaced from the adjacent ends of the side bowed bars of the crutch) additionally reinforces the thimble tip.

A further object of the invention is the provision of a rubber cap to the lower end of the thimble tip.

In practical fields the details of construction may necessitate alterations falling within the scope of what is claimed.

The invention comprises further features and combination of parts as hereinafter set forth, shown in the drawings, and claimed.

In the drawings:—

Fig. 1 is a view in side elevation of a crutch showing the spring tensioned tip applied to the lower end.

Fig. 2 is an enlarged detail sectional view through the spring tensioned tip.

Fig. 3 is a sectional view on line 3—3 of Fig. 2.

Fig. 4 is a sectional view on line 4—4 of Fig. 2.

Referring more especially to the drawings 1 and 2 designate the bowed side bars of the crutch, to the upper ends of which the armpit head 3 is attached in any suitable manner. Secured by any conventional means between the bowed side bars, between the upper and lower ends of the crutch is a usual hand grip 4. The lower ends of the side bars 1 and 2 are brought together and secured by means of the bolts 5, there being

a filling piece or block 6 (which is V-shaped) secured also by the bolts 5 in the V-shaped crotch 7 between the lower ends 8 of the bowed side bars 1 and 2. The end portions 9 of the side bars 1 and 2 are in parallelism to each other, and are semi-circular in cross section. These parallel portions 9 are provided with slots 10 which are in registration, and of the same length, and since the parts 9 are in parallelism and secured together and being semi-circular, it is to be noted that the outer circumference of the lower end of the crutch is cylindrical. A sleeve 11 is fitted upon the adjacent end parts 9, and secured thereto by the headed transverse pin 12, which passes through the contracted part 13 of the sleeve and assists in additionally securing the end parts 9 together. The enlarged part 14 of the sleeve 11 is spaced from the exterior cylindrical surface of the lower ends of the crutch bars thereby providing a guide space 15 for the tip thimble 16, which telescopes into the sleeve 11 and over the lower ends of the crutch bars. A transverse headed pin 17 extends transversely of the slots 10, normally engaging the lower ends of said slots, while the headed ends 18 are secured as shown in diametrically opposite portions of the tip thimble. By means of the pin 17 downward detaching of the tip thimble is prevented, as well as preventing rotation of the tip thimble relative to the lower end of the crutch. The transverse pin 17 also guides and reinforces the tip thimble. The sleeve 11 assists in guiding and reinforcing the thimble 16. A coil spring 19 is interposed between the lower end 20 of the thimble 16, and the lower end of the crutch 95 and located within the thimble, thereby holding the thimble normally extended. The lower part of the thimble 16 terminates in a heavy solid portion 21, constituting a crutch foot, which is of a tapered shape 100 such as indicated at 22, and is designed to wear a rubber shoe cap 23, the upper outwardly flared portion 24 of the wall 25 of which engages the curved shoulder 26, which is adjacent the foot of the thimble 16. 105 By means of this shape of foot the rubber cap shoe is retained in place on the foot, and constitutes means to prevent slipping of the crutch. The coil spring 19 acts to cushion the crutch, when the shoe is applied to the ground or pavement, thereby relieving the jar on the shoulders of the user.

The invention having been set forth what is claimed as new and useful is:—

The combination with a crutch having its lower cylindrical end provided with a transverse vertically disposed slot, of a sleeve, secured to the lower end of the crutch and having an enlarged cylindrical portion spaced from the exterior cylindrical surface of the lower end of the crutch, a hollow tubular thimble tip telescoping the lower end of the crutch and into the space between the enlarged portion of the sleeve and the lower end of the crutch, means for securing the sleeve to the lower end of the crutch, a pin 10 extending transversely of the slot and hav-

ing heads secured in diametrically opposite portions of the upper end of the thimble tip, a coil spring located in the thimble tip and interposed between the lower closed end of the tip and the lower end of the crutch and a rubber shoe carried on the lower end of the thimble tip. 20

In testimony whereof I have signed my name to this specification in the presence of two subscribing witnesses.

MOSE BRUYERE.
